UNITED STATES PATENT OFFICE.

WILLIAM HERBERT SANDFORD, OF NEW YORK, N. Y.

HANDLE OF GOLF-CLUBS, POLO-STICKS, AND THE LIKE.

1,102,441.

Specification of Letters Patent. Patented July 7, 1914.

Application filed July 21, 1913. Serial No. 780,357.

To all whom it may concern:

Be it known that I, WILLIAM HERBERT SANDFORD, a subject of the King of Great Britain, residing in New York city, State of New York, and whose post-office address is 606 West One Hundred and Thirteenth street, New York city, United States of America, have invented certain new and useful Improvements in or Relating to the Handles of Golf-Clubs, Polo-Sticks, and the like, of which the following is a specification.

This invention consists in a simple device for holding a grip member of a golf club shaft secure and preventing the hands of a user of the club slipping.

It will be described with reference to the accompanying drawing, in which—

Figure 1 is an elevation of the handle portion of a club shaft with the invention applied. Fig. 2 is a cross section through the shaft and holding device and Fig. 3 is a longitudinal section thereof.

The device consists of a ferrule 3 of rubber or other material affording a grip to the user's hand which ferrule is partly divided or split in two so as to form an inner and outer covering for a cord or equivalent binding 4 used for securing the end of the usual grip member 2 applied to the handle portion of a shaft of golf clubs, polo sticks or the like. The division between the two coverings commences, as shown in Fig. 3, at one edge of the ferrule and the internal surfaces of the coverings are, preferably, shaped to receive snugly the binding cord 4, which when bound upon the inner covering secures both the grip member 2 and the ferrule in place.

In using the device, the grip member 2 is first suitably secured, as by tacks 6, to the shaft, the rubber or other ferrule 3 is then placed over the end portion of the grip, Fig. 3, and secured to the grip by the cord bind-

ing 4. After the outer covering, previously lifted or turned back for the insertion and manipulation of the cord binding, has been turned down on to the cord binding, a reunion or firm joint preferably water-tight, is made, as indicated at 5, between the outer and inner coverings or parts of the ferrule by means of rubber solution. The binding is thus kept well protected and in good condition.

Having thus described the nature of the said invention and the best means I know of carrying the same into practical effect, I claim:

1. A device for holding a grip member secure on the handle portion of the shaft of a golf club polo stick or the like, consisting of a ferrule of a material affording a grip to the hand of a user, said ferrule being partially divided to form an inner and outer covering and applied to the end portion of the grip member, a binding member interposed between said coverings and adapted to clamp the ferrule and the grip member to said handle portion.

2. In combination with the handle portion of the shaft of a golf club, polo stick or the like, a grip member on said handle portion, means of securing the grip member to the shaft, a partially divided ferrule of material affording a grip or hold to the hand of a user and forming inner and outer portions, means interposed between the said portions of the ferrule and adapted to bind said inner portion against the grip member and means adapted to re-unite said two portions.

In testimony whereof I have signed my name to this specification in the presence of two subscribing witnesses.

WILLIAM HERBERT SANDFORD.
